UNITED STATES PATENT OFFICE

JOSEPH KNOCHE, OF KANSAS CITY, MISSOURI

DESIGN FOR A FRONT FOR DISPLAY DEVICES

Application filed January 19, 1931. Serial No. 38,382. Term of patent 7 years.

To all whom it may concern:

Be it known that I, JOSEPH KNOCHE, a citizen of the United States, residing at Kansas City, in the county of Jackson and State of Missouri, have invented a new, original, and ornamental Design for Front for Display Devices, of which the following is a specification, reference being had to the accompanying drawing, forming a part thereof.

The figure is a front face view of a front

for a display device showing my new design.

The device is substantially thin and generally flat.

I claim the ornamental design for a front for a display device substantially as shown and described.

In testimony whereof I hereunto subscribe my name this 13 day of January, 1931.

JOSEPH KNOCHE.
